Primary Examiner—A. Hugo Word
Assistant Examiner—Lavone D. Tabor
Attorney, Agent, or Firm—Lee R. Osman[57] **CLAIM**

The ornamental design for a handle for an electric toothbrush, as shown and described.

DESCRIPTION

FIG. 1 is a perspective view of a handle for an electric toothbrush embodying our new design;

FIG. 2 is a top plan view thereof;

FIG. 3 is a right side elevational view thereof; the left side being a mirror image thereof;

FIG. 4 is a bottom plan view thereof;

FIG. 5 is a front end view thereof; and,

FIG. 6 is a rear end view thereof.
